US00D638381S

(12) **United States Design Patent**
Kuzuoka

(10) **Patent No.:** **US D638,381 S**
(b4) **Date of Patent:** **** May 24, 2011**

(54) **ELECTROLUMINESCENCE MODULE**(75) Inventor: **Yoshikazu Kuzuoka**, Kadoma (JP)(73) Assignee: **Panasonic Electric Works Co., Ltd.**,
Kadoma-shi (JP)(**) Term: **14 Years**(21) Appl. No.: **29/376,610**(22) Filed: **Oct. 8, 2010**(30) **Foreign Application Priority Data**

Apr. 9, 2010 (JP) 2010-009120

(51) **LOC (9) Cl.** ..... **13-03**(52) **U.S. Cl.** ..... **D13/180; D13/182**(58) **Field of Classification Search** D13/180,

Primary Examiner — Selina Sikder(74) *Attorney, Agent, or Firm* — Marvin A. Motsenbocker;
Mots Law, PLLC(57) **CLAIM**The ornamental design for an electroluminescence module,
as shown and described.**DESCRIPTION**

FIG. 1 is a front perspective view of an electroluminescence module;

FIG. 2 is a front view thereof;

FIG. 3 is a right side view thereof;

FIG. 4 is a top plan view thereof;

FIG. 5 is a rear view thereof; and,

FIG. 6 is a bottom plan view thereof.

A left side view of the electroluminescence module is a mirror
image of the right side view, and therefore omitted.**1 Claim, 6 Drawing Sheets****FIG.1**
